[57] CLAIM

The ornamental design for a reel hub for a tape cassette, as shown and described.

DESCRIPTION

FIG. 1 is a front and right-side perspective view of a reel hub for a tape cassette, showing my new design; FIG. 2 is a front elevational view thereof, the rear view being a mirror image thereof; FIG. 3 is an elevational view in cross section taken along section lines 3—3 of FIG. 2; FIG. 4 is a left-side elevational view thereof, the right-side being a mirror image thereof; FIG. 5 is a top plan view thereof; and, FIG. 6 is a bottom plan view thereof.

FIG. 1

FIG. 2

FIG. 3

FIG. 4

FIG. 5

FIG. 6
